[57] CLAIM

The ornamental design for a combined windshield wiper arm and air foil, as shown and described.

DESCRIPTION

FIG. 1 is a top plan view;

FIG. 2 is a right side elevational view;

FIG. 3 is a bottom plan view;

FIG. 4 is a left side elevational view;

FIG. 5 is a section taken at line 5—5 of FIG. 4; and,

FIG. 6 is a bottom, right side perspective view.

The broken line showing of environmental structure in the drawing is for illustrative purposes only and forms no part of the claimed design.

FIG. 1

FIG. 2

FIG. 3

FIG. 4

FIG. 5

FIG. 6
